UNITED STATES PATENT OFFICE

DANIEL BAKER DIMICK, OF BIRMINGHAM, ALABAMA

CORE MOLDING MACHINE

Original application filed October 23, 1929, Serial No. 401,767. Divided and this application filed December 23, 1930. Serial No. 504,391.

The present invention relates to improvements in core molding machines, and is a division of my copending application entitled "Method and apparatus for casting pipe", Ser. No. 401,767, filed October 23, 1929.

It is an object of the present invention to provide an improved core molding machine, in which a bell core is formed for cast iron pipe, useful in connection with the mold described in my application aforesaid.

It is another object of the invention to provide an improved machine for molding a bell core having a pour basin and depressions for forming locking keys on the bell of the pipe.

With the foregoing and other objects in view, the invention will be more fully described hereinafter and will be more particularly pointed out in the claims appended hereto.

In the drawings, wherein like symbols refer to like or corresponding parts throughout the several views,

Figure 1 is a front elevation, with parts broken away and parts shown in section, of an improved core molding machine constructed in accordance with the present invention.

Figure 2 is a view similar to Figure 1, but with the bell core pattern keys drawn back into the mold stripping position, and the completed combined bell core and pour basin mechanically stripped or lifted from the core box section of the machine, ready to be removed to its place in a flask mold.

Figure 3 is a top plan view of the improved bell core box used, showing also the bell core keys.

Figure 4 is a section taken on the line 4—4 in Figure 3, with the bell core keys removed, and

Figure 5 is also a sectional view taken on the line 5—5 also in Figure 3.

Referring more particularly to the draw-

ings, the runner box is shown at 48. This runner box 48 may be a combination of cast iron and steel of such form as to support the tempered molding sand 49, when rammed to the shape and size desired to make a combined bell core and pour basin. At 50 are shown the impressions made in the bell core by the bell locking key patterns, leaving cavities of the size and in the position desired for bell locking keys. The pour basin is indicated at 45a.

Now the runner box 48 and its core are prepared upon the machine shown in Figures 1 and 2. This machine includes in its construction a core box 53, which core box is more particularly shown in Figures 3, 4 and 5. The inside of the core box is machined to the size and shape of the bell core desired. A flange 54 is provided on the core box to center the runner box 48. The core box slidably supports the tapered locking key patterns 55 for the bell core. These key patterns 55 are mounted for radial sliding movement in the core box and crank handles 56 are provided for shifting the key patterns 55 back and forth, such handles 56 being provided with threaded shafts 57, which engage thorough threaded openings in portions 58 of the key patterns, the threaded shaft being held against longitudinal motion by the end collars 59, but, of course, being free to be rotated. The bottom or table 60 for the runner box is adapted to receive and support the same and is carried by the spider 61.

The supporting legs 62 for the core box are erected upon the bed plate 63 of the machine. This bed plate supports a hydraulic or other cylinder 64 having the plunger 65 therein coupled to the plunger rod 66 to which the spider 61 is affixed. The upper end of the plunger rod 66 moves in a guide sleeve 67. The guide sleeve 67 forms the hub of the core box. The cover 68 of the cylinder 64 limits the upward travel of the

piston 65. A dust cap 69 may be provided on the hub 67 of the core box.

The core box is machined to give the shape and size of the bell core desired and has recesses 87 machined in its upper surface to receive the bell locking key patterns 55.

This core box is shown more particularly in Figures 3, 4 and 5.

The key patterns 55 are held in angular relation one with the other, but are free to slide toward and away from the center of the core box. The projecting ends of these key patterns are machined to the size and shape of the bell locking keys desired. By 15 rotating the cranks 56, through the threaded engagement of the shafts 57 with the lugs 58, the key patterns may be advanced or retracted and thus moved toward or away from the center of the core box on radial lines. The outer surface of the inner ring of the core box is machined to fit the bore of 20 the runner box 48.

In the molding of the combined bell core and pour basin, the bell key patterns 55, shown in Figures 1 and 2, are moved in by 25 turning crank 56 until they project inside the core box 53 to the thickness of the keys desired, the core bottom plate being in its lowest position, as shown in Figure 1.

30 The runner box 48 is centered by the inner ring 54 of the core box and is supported on its outer ring by the top of the core box 53 and on its inner ring by the platform or core bottom ring 60 which acts as a stripping plate. Tempered molding sand 49 is rammed in the runner box, the sand taking the shape of the bell core desired. Gates for either top or bottom pouring, as desired, are molded in the runner box, and the pour 35 basin in the upper sand in the runner box is shaped to give the molten iron an unrestricted path of travel around to the gates evenly. After ramming the sand, the key patterns 55 are drawn back by means of the 40 cranks 56 to the position shown in Figure 2, leaving impressions 50 in the bell core to make the bell locking keys. Compressed air is admitted beneath the piston 65, raising the piston, the rod 66, the core bottom or 45 stripping plate 60 and the combination bell core and pour basin, as shown in Figure 2.

This combination bell core and pour basin is now ready to be placed on the completed flask mold, as described in my copending 50 application aforesaid.

After removal of the completed bell core, the core bottom plate is lowered by gravity upon the release of the compressed air under the piston 65, thereby completing the molding cycle of the combined bell core and pour basin.

The combined bell core and pouring basin, as molded in the runner box 48, is now placed in the completed flask mold. The completed 55 pipe mold is now ready for pouring.

After pouring, the runner box 48 is removed and returned to the bell core molding machine.

It will be obvious that various changes in the construction, combination and arrangement of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. A bell core molding machine, comprising a bell core box, locking key patterns movably carried by said box, a shiftable table moving through said bell core box for carrying a runner box, and means for moving said table.

2. A bell core molding machine, comprising a bell core box, a table moving therethrough for supporting a runner box, and a plurality of radially shiftable locking key patterns carried by said bell core box and forming impressions in the sand in said runner box when in a lowered position.

3. A bell core molding machine, comprising a bell core box, a table shiftable vertically through said box for supporting a runner box, locking key patterns distributed horizontally about said bell core box and moving radially with respect to the center of the box and acting to form impressions in the sand in said runner box, and means whereby said patterns may be shifted back and forth.

4. A bell core molding machine, comprising a bell core box, locking key patterns movably mounted in said box, a shiftable table moving through said box for supporting a runner box, and a power ram for actuating said table.

5. A bell core molding machine comprising a bell core box having a substantially flat upper molding surface to receive the molding material directly thereon, said surface having slots opening upwardly therethrough, key patterns moving radially in said slots, a movable table for directly supporting a runner box in which the combined bell core and pour basin is rammed, said table moving through the bell core box, and means for moving said table.

6. A bell core molding machine comprising a core box having an upper surface for receiving the rammed sand and having radial slots therein, key patterns slidable radially in said slots and exposed on the upper surface of the box, a table normally below the surface of said box for receiving a portion of the rammed sand and also supporting a runner box in which the sand is rammed, and means for moving said table to eject the runner box after the ramming operation.

7. A bell core molding machine comprising a core box having an upper annular surface

for directly receiving the rammed sand thereon and having radial slots in said surface, key patterns movably mounted in said radial slots, means for shifting said key patterns so as to extend inwardly of the annular surface, a table supported inwardly and normally below said surface for receiving directly thereon the rammed sand inwardly of the annulus and also for receiving a portion of a runner box in which the sand is rammed, and means for moving said table to eject the runner box and core after the molding operation.
